United States Patent Office

Des. 191,765
Patented Nov. 14, 1961

191,765

CIGARETTE LIGHTER OR SIMILAR ARTICLE

Devendra Nath Sharma, 22 Carroll House,
Gloucester Terrace, London, England

Filed Jan. 7, 1959, Ser. No. 54,057

Term of patent 14 years

(Cl. D48—27)

FIG. 1

FIG. 2

FIG. 1 is a perspective view of a cigarette lighter showing my new design; and

FIG. 2 is a top plan view showing the body of the cigarette lighter pivoted into a position perpendicular with the base.

I claim:

The ornamental design for a cigarette lighter or similar article, as shown and described.
